Primary Examiner — Bao-Yen T Nguyen

(74) Attorney, Agent, or Firm — Suzanne Kikel, Patent Agent

(57) **CLAIM**

The ornamental design for a display screen or portion thereof with a graphical user interface for a house appliance monitoring APP for use on a display screen or portion thereof, as shown and described.

DESCRIPTION

The patent or application file contains at least one drawing executed in color. Copies of this patent or patent application publication with color drawing(s) will be provided by the Office upon request and payment of the necessary fee.

The single FIGURE is a front view of a display screen or portion thereof with a graphical user interface for a house appliance monitoring APP showing my new design.

The broken line showing of a display screen and cell phone form no part of the claimed design.
